BAFFLE MOUNTING FOR AIR CIRCULATOR UNITS

James C. Brittingham, St. Louis, Mo.

Application October 20, 1943, Serial No. 507,225

15 Claims. (Cl. 230—274)

This invention relates to improvements in baffle mounting for air circulator units, and more particularly to an improved floating arrangement of baffle elements utilized in room air circulators, usually in functional combination with motor-driven fans.

Each of the more usual and widely sold types of portable room air circulating units embodies an electric motor of vertical shaft type, a propeller fan driven thereby, and a baffle arranged across the fan discharge stream in such manner as to cause deflection of the air delivered by the fan, in a generally annular pattern of a somewhat upward trend. Until recently, with but few unimportant exceptions, no provisions were made for varying the pattern of the air stream discharged from the unit, nor for selectively directing the air stream. For this reason, even though it is frequently desirable to direct all or a major part of the fan output in a given direction from the unit, this was nevertheless impossible of attainment by any fully satisfactory means. It is accordingly a major object of the present invention to enable, automatically under at least certain conditions, the direction of the air stream from a circulator unit of the type in discussion, in a more or less defined beam or path directed for maximum comfort, and without material loss of the full displacement effect of the fan.

Another object of the invention is attained in provisions for a self adjusting baffle in a room circulator, such as to render the unit automatically capable of shifting the direction of a major part of the air stream, when the unit is placed near external obstructions such as a wall or partition, or when obstructed on more than one of its sides, as when located in the corner of a room or other enclosure. In keeping with this object, an improved baffle mounting provides for a self-varying angularity of baffle resulting in an automatically directional damping device.

Yet another important object of the invention is attained in an arrangement of fan and baffle in a unit of the general type described, such as to obtain an effect corresponding substantially to that of an oscillating type of desk fan, yet not requiring any translatory movement of the fan, nor any mechanical actuation of the cooperating baffle.

Yet an additional object of the invention is attained in combination with some or all of the agencies identified with attainment of the foregoing objects, and in combination therewith an improved arrangement for varying a tentatively fixed angularity of baffle in a room air circulator unit.

A further important object of the invention is attained in an improved design of tiltable baffle member designed particularly for use in air cir-

culator units, the baffle being formed to provide linear air directing channels defined in part by protuberances on the baffling surface; the improved construction of baffle further including particularly-shaped marginal portions adapted to effect delivery of the deflected air stream at a more desirable angle, and in a more favorable pattern.

Yet another object of the invention may be stated as attained in a pendularly mounted baffle and improved mounting means therefor, in such a combination that the baffle is located in the discharge stream of the fan, in such a relation as to attain a novel air-directing and -deflecting result, but without back-pressure effects on the fan, thus providing for a "free-air" relationship of the fan to the other elements of the unit.

The foregoing and numerous other objects will more clearly appear from the following detailed description of a preferred embodiment of the improvements in a circulator unit, particularly when the description is read in conjunction with the accompanying drawing, in which:

Fig. 1 is a top or plan view of a room-air circulator of portable type, embodying present improvements;

Fig. 2 is a side elevational view, partly in section, of the assembly or unit, and

Fig. 3 is a fragmentary sectional view of the assembly, as taken on line 3—3 of Fig. 1.

Referring now by characters of reference to the drawing, the present improvements are by preference although not strictly necessarily embodied in a portable room air circulating unit, in which, as illustrated, there is a frame including four, but if desired, some fewer or more, upright or pillar elements, two of which are indicated at 10 and 11 respectively and two more generally indicated at 12 and 13; the latter columns are for reasons hereinafter better appearing, extended upwardly somewhat beyond the elements 10 and 11. The vertical columns are structurally secured in angularly spaced relation through a pair or more of frame bands, one being shown at 14 at the lower portion of the frame, and another at 15 in an upper portion. The frame bands 14 and 15 are shown as securely attached to the uprights by means of rivets or the like 16.

A cylindrical grille element 17 is supported by, 50 securely fixed to and serves to bridge the frame bands 14 and 15. This grille may assume a variety of forms, but is shown as constructed of sheet metal, profusely apertured, and is provided with grille-like end members 19 and 20.

Suspended from the lower band 14 or if desired, directly from the columns 10, 11, 12 and 13, or some thereof, are a plurality of motor-supporting arms 21 which are conveniently bolted to the frame of the motor 22 at their inner ends, and secured as by certain of the rivets

16, either to the band 14 or to some or all of the uprights 10, 11, 12 and 13.

As will appear, and in keeping with frequent practice now well known, the motor shaft which is vertical, extends upwardly from the motor frame 22, being indicated as 23, and at or near its outer end serves to carry and to rotate, a propeller type fan generally indicated at 24. Such adjuncts as make for convenience of lifting the unit from place to place, and for other purposes, may be added as desired, but are not of themselves material to the present invention. It may however be noted as desirable to provide a motor controlling unit generally indicated at 25 embodying a control knob 26, and providing for a plurality of different motor speeds whereby to regulate the fan speed, hence to govern air delivery by the unit.

While most usefully employed in functional combination with the elements described, the present improvements are identified principally with the baffle mounting and structural provisions for a novel function of the baffle as will now be described.

It is contemplated that in normal use the baffle, generally indicated at 30, shall be floatingly and pendularly mounted transversely of the air stream delivered, preferably upwardly as by fan 24. By preference, but obviously not necessarily, the baffle 30 is substantially circular in plan, and in the example shown, its face portion encountered by the air stream is of a substantially planar aspect. The baffle 30 is provided with a pair of upwardly extended supporting arms 31, each of which is apertured to receive a bearing or otherwise constitute a journaling portion, co-acting with a pivot rod, later described. The baffle 30 is further preferably provided with a plurality of parallel, spaced depending, protuberant rib or flange portions which may be formed integrally with the body of the baffle, and are generally designated at 32. This provision is of distinct advantage in a tilttable baffle, in that it tends to resolve the rotary components of motion of the fan stream, so as, to a greater extent, to straighten and definitely to direct the air stream, particularly when the baffle is tilted.

A further improvement in construction of the baffle 30, is seen in the provision of slightly downturned lip elements 33, there being one of these by preference on each of the opposite margins of the baffle 30 in locations remote from the pivot axis of the baffle. It will now readily appear that, when the baffle is depressed at one side of the unit, the lip formation 33 at the high side of the baffle, will tend markedly to deflect toward the horizontal, the stream of air delivered from the lip-carrying margin of the baffle.

The baffle is further preferably formed in order to permit a freedom of swinging movement, with a pair of oppositely disposed apertures or slots 34, each of these being of a size to receive therethrough the adjacent upright element such as 12 or 13, by which the baffle is supported through the agency of a pivot rod 35. It will now readily appear that the extremities of the slotted openings 34 will, at either extreme of oscillation of baffle 30, coat with the adjacent upright element 12 or 13, in a manner definitely to limit the range or amplitude of swinging motion of the baffle.

Another preference in constructing the baffle, is that it shall be somewhat greater in area, and if circular, of a somewhat larger diameter, than the diameter of the fan 24. As one example of

this relationship it has been found that, with the parts proportioned and spaced substantially as shown by the drawing, when utilizing a 10" propeller type fan 24, the baffle should be at least 5 of an area corresponding to that of a circular baffle of 15" diameter.

The design of the baffle and the axis rod element 35 therefor is such that the baffle is supported in the unit and directly in the line of air discharge flow from the fan, in a condition of delicate or sensitive physical balance, and by further preference, is mounted in such a manner that friction at rest is minimized. Provision to this end is made in the structure illustrated by 10 disposing say a pair of spaced bearing assemblies which are of rolling antifriction type, such as ball bearings, these being generally indicated by 15 at 36 and 37. Each such assembly includes by 20 preference an inner race and an outer race, the inner race serving to receive the shaft or rod 35 and the outer race welded, riveted or otherwise secured, preferably to the adjacent arm 31. It will now have clearly appeared that, assuming the rod 35 to be stationary, the baffle is free to 25 oscillate under influence of fluctuations of air velocity and pressure on its different portions on opposite sides of its supporting pivot.

For the purpose of rendering the baffle sensitive to effects tending to cause occasional oscillations thereof about its axis, it will have 30 appeared as desirable that the baffle be formed with its center of mass and center of gravity located appreciably below, and in the relation of a pendulum to the axis of baffle oscillation, in the present example, this axis being identified with the rod 35. This results from the fact that the rod 35 is, when a circular baffle is utilized, extended diametrically of but somewhat above the baffle, so 35 that equal masses of the latter are disposed on opposite sides of the rod.

It will now have appeared that the upwardly projecting arms 31 by which the baffle 30 is directly supported, result in the behavior of the baffle somewhat in accordance with the laws governing pendular motion. This effect is of course modified by the effect of the air pressure on the baffle, particularly uneven air pressures on different portions of the baffle. Having in mind that, under most conditions of usage, with the 40 fan 24 rotating at a uniform selected speed, the baffle will assume an oscillatory or swinging movement, it may be desirable as a matter of personal preference of the user, to be able to regulate or adjust the amplitude, and hence the period 45 or frequency of motion of the baffle. This result is conveniently accomplished by providing baffle 30 with a depending threaded rod or the like shown at 38, threadedly engaging which, for 50 purposes of adjustment, is a counterweight nut 39. This need be only of moderate mass, and it has been found that the rod 38 need be of no great length since the action of the baffle is nicely sensitive even to minor adjustments of the counterweight 39 on the rod 38. It will be understood that the device is operative without this 55 added convenience and facility for adjustment, although the feature is highly desirable.

As a convenient means of assembling the pivot-forming rod 35 to the frame of the unit, the 60 ends of the rod may be threaded and extended through suitable transverse openings 43 in the opposite paired columns or uprights 12 and 13. Nuts 44 may be employed in threaded engagement with the ends of the rod 35, whereby 65 through clamping actuation of the nuts 44 the

rod 35 may be fixedly positioned with respect to the frame. If desired, a plurality of different sets of the apertures 43 may be provided, to permit, by setting the rod in different sets of openings, a vertical adjustment of the baffle distantly with respect to the fan.

Due to special conditions existing in a given room or other enclosure, it may at times be desirable to fix the angular position of the baffle 30 with respect to the fan stream. Under such conditions it is merely necessary to thread downwardly each of the one or more baffle clamping screws 45 so as to bring the end of the screw into firm contact with the underlying portion of rod 35. The screws 45 each extends threadedly through a tapped bushing or nut 46 which may be welded into a suitable opening therefor in a cover member 47, or some equivalent structure employed to protect the bearing assemblies 36 and 37. The desired fixed angular position of the baffle 30 is first determined by effect, then with the baffle manually positioned at the desired angularity, the locking screws 45 are actuated as described.

Proceeding now with a description of the normal function of the exemplary embodiment of the improvements, it results from the fact of the sensitively balanced mounting of the baffle about its axis that the air stream from the fan 24, in perfectly quiet ambient air and with no obstruction of any nature in or near the unit, the air pressure against the sides of the baffling surface of member 30 will be exactly equal. Thus the balanced condition of the baffle tends at all times to keep it stationary, and when used with a vertical fan as shown, in a horizontal plane.

In practice, however, the condition just described is at nearly all times and in nearly all locations only theoretical. Experience in numerous trials over a protracted period of usage of a device such as that illustrated, indicates that normal movements of air in a room, and the rebound effect from obstructions to the air stream, even those relatively remote from the unit, are such as to produce frequent disturbances of the uniform air stream delivered by the fan. From this it results that under practically all conditions when the fan 24 is operating, the baffle 30 will exhibit an oscillating motion about its axis, the obvious effect of which, on the room occupants, approximates that of an oscillating desk fan. The condition just described obtains only in case the unit is not disposed close to a wall, piece of furniture, or other similar object. In the latter case the baffle becomes self-positioning or self-adjusting in angularity. Due to the drop in velocity on the obstructed side of the unit, that side of the baffle will sharply dip, the baffle will become relatively stationary in a tilted position, and will serve advantageously to deliver the major part of the air stream in the direction of the high side of the baffle. A comparison of a unit equipped with the present improvements with older types, in which either the baffle is fixedly horizontal or is susceptible of only manual placement at different angles, reveals a marked improvement in the automatically adjusting feature of the current subject matter. In the event of automatic dip of the baffle as described, resulting in the described effect of self-damping of the air flowing toward the obstructed side of the unit, there is but a negligible loss of total air delivery by the unit. The present improvements thus automatically prevent the delivery of substantial proportions of

the total air stream, in unwanted directions radially of the unit.

As heretofore noted, it is a preference to construct the baffle of a considerably greater area than the diameter of the fan or other displacement agency. The reason for this preference in relative diameter of fan and baffle, arises in substantial degree by reason of an important feature of construction and combination, namely, the provision of a secondary or auxiliary baffle 50. This member is preferably an inverted frustoconical deflector, but may be of other suitable, even planar form, preferably of two parts, mounted centrally of the unit, and in the upper head or end portion 19 of the enclosure about the fan, as by the bolt 51, through which the two parts of the baffle are clamped to the element 19.

This auxiliary baffle 50 has an effect of diverting the air radially outwardly and upwardly, so that the principal impact effect of the resulting annular stream therebeyond, is upon the peripheral or marginal areas of the baffle 30 and only to a very minor extent centrally thereof. Although the baffle 30 is operative with a considerably improved effect and with many advantages over stationary baffle structures heretofore characterizing the art, in the absence of baffle 50, the provision of the auxiliary baffle serves to make the baffle 30 considerably more readily and definitely responsive to the fan stream than would otherwise be the case. But for the provision of the auxiliary baffle 50, the free oscillating action of baffle 30 is in a measure undesirably responsive to strong drafts of outside air and similar uncontrollable effects, whereas the provision of the auxiliary baffle 50 serves distinctly to bring the oscillating or angular adjusting action of baffle 30 solely under the control of the fan. It thereby serves practically to eliminate unwanted effects of stray air currents.

It will now have appeared that the improvements presently selected for description, serve fully to attain each of the several objects and advantages above specifically stated, as well as other important improved results implied from the description of parts and their arrangements.

Although the invention has been described by making detailed reference to a single preferred embodiment thereof, the detail of description is to be understood solely in an instructive and not in any limiting sense, numerous variants of structure and function being possible within the scope of the claims hereunto appended.

I claim as my invention:

55. 1. In a portable air circulator unit including a vertical-shaft fan and fan driving means, a normally horizontal baffle at least coextensive with the disc area of the fan, and pivotal supporting means by which the baffle is mounted in balanced condition in the unit transversely of the fan stream, and being so arranged that substantially equal areas of the baffle are located on opposite sides of the pivotal supporting means, whereby the fan stream normally acts to maintain the transverse position of the baffle.

60. 2. In an air circulator unit of portable type, a horizontal propeller fan and driving motor therefor, a baffle of an area to extend substantially fully across the fan stream, for directing the air stream of the fan in an annular direction about the unit, with the fan arranged to deliver the air stream against the baffle and outwardly thereof in substantially a free-air arrangement, and pivot means for mounting the baffle with substantially equal baffle surface on opposite sides of the pivot

axis, and with the baffle relatively sensitively balanced about its axis, whereby the baffle is arranged to dip in response to a reduction of air flow toward any region of obstruction laterally beyond the baffle, and to dip toward such region of relative obstruction while correspondingly raising an opposite portion of the baffle, whereby to provide for an increase of air flow toward the relatively unobstructed regions beyond the unit.

3. In combination in a portable air circulator unit including a vertical-shaft propeller type fan and fan driving means, a baffle, means providing a pivotal support for the baffle along a horizontal axis, and maintaining the baffle in a condition of sensitive balance normally in a position transversely of the fan air stream, and considerably upward of the fan, the baffle being of a substantially greater area than the area of the fan circle.

4. In combination in a portable room air circulator, including a vertical shaft fan and fan driving means, a circular baffle, means providing a substantially horizontal, diametral pivot axis about which the baffle is freely movable, and the baffle being of such form and provided with an auxiliary pendular weight so arranged that the center of gravity of the movable baffle structure lies below its axis of movement, whereby the baffle is suspended in pendular relation.

5. In an air circulator unit, a fan and driving motor therefor, a pendularly mounted baffle spaced from the fan in the discharge stream thereof, and a relatively smaller auxiliary baffle disposed between the fan and said pendularly mounted baffle.

6. In an air circulator unit, a fan and driving means therefor, a baffle mounted for free swinging movement beyond the fan in the discharge stream thereof, and being of substantially larger area than that of the fan circle of said fan, and an auxiliary deflector of substantially lesser area than that of the fan circle and located substantially inwardly from the swingable baffle.

7. In an air circulator unit, a fan and driving means therefor, a sensitively balanced pendularly mounted deflector located across the discharge region of the unit, and an auxiliary deflector of a substantially frusto-conical type, located appreciably inwardly of the first said baffle and across the center area of the fan stream.

8. In a portable air circulator unit, a propeller type fan and fan motor, a baffle of an area at least approximating the disc area of the fan, and bearing a substantially free air relation to said fan, and disposed substantially beyond the fan as and part of a pendular system of baffle support, said pendular system including a pivot structure providing an axis of baffle movement which lies across and substantially intermediate the baffle area, and means for adjusting the effective length of the pendulum system of which the baffle is a part.

9. The combination and arrangement of elements substantially as recited by claim 8 in which the baffle is supported to provide equal surfaces on opposite sides of a horizontal axis, and the means for adjusting effective pendulum length, is comprised of a threaded rod dependingly supported by the baffle, and a threaded weight adjustably carried by the rod.

10. In an air circulating unit, a fan, driving means for the fan, a baffle pivotally mounted in

the air stream of the fan somewhat forwardly thereof, and so arranged for tilting movement for various angular presentations to the fan stream, the baffle being provided with a plurality of substantially rectilinear air directing surfaces each of which is of a trend substantially at a right angle to the pivot axis of the baffle.

11. In a circular unit including a fan and fan motor, a baffle press-formed of a sheet material, means for mounting the baffle in the unit in a selectively tiltable relation, the baffle being formed to provide a plurality of spaced integral linear protuberances from its deflecting surfaces, said protuberances being of such location and spacing as to define linear channels therebetween.

12. In an air circulator unit including a fan and fan motor, a baffle mounted for tilting movement so as to be disposable in various angular positions across the air stream, the baffle being characterized by oppositely disposed downturned lip formations on its opposite margins remote from its axis of tilting movement, said margins being formed, when the baffle is tilted, so that one thereof serves to direct the air emanating from the unit in a more nearly horizontal trend than the major remaining surface of the baffle.

13. In an air circulator unit including a fan and fan driving motor, a baffle adapted to be tilted about an axis for various angular presentations to the air stream from the fan, whereby variously to direct the air stream deflected by the baffle, the baffle being characterized by a plurality of rectilinear surfaces tending to channel or beam the air stream delivered by the unit as a result of the deflecting action of the baffle, and further provided with a pair of opposite, downwardly turned marginally disposed deflector lips operable selectively, when the baffle is tilted, to impart a horizontal component of movement to the baffle-deflected air stream.

14. In a portable room air circulator unit including a vertical-shaft, horizontal fan, a fan motor, a circular baffle arranged in the unit to extend substantially fully across the fan stream, an axis element on which the baffle is normally horizontally mounted in a state of sensitive balance, and antifriction bearings of rolling type, serving to journal the baffle in floating relation on the axis element thereof.

15. In a room air circulator unit of portable type, a frame structure including a pair of upright frame members, a fan and fan motor carried by the frame, and mounted for initial delivery of air upwardly through the unit, a baffle in the upper portion of the unit, swingably mounted across the fan discharge stream, the baffle being provided with a pair of upwardly extending arms, and pivot-forming elements by which the baffle arms and the upright frame members are connected to permit free oscillating movement of the baffle, the baffle being substantially circular in transverse aspect and formed to present a deflecting area to the fan stream substantially greater than the area of the circle of the fan, and of greater area than the plan area of the frame, the frame including a pair of baffle-supporting upright elements and the baffle being provided with oppositely arranged slotted openings through which said uprights extend in such manner that the ends of the slots serve to limit the range of swinging movement of the baffle.

JAMES C. BRITTINGHAM.
